UNITED STATES PATENT OFFICE.

GUY P. SLATER, OF SAND SPRINGS, OKLAHOMA.

THROWING-OFF DEVICE.

Application filed July 23, 1926. Serial No. 125,498

The object of this invention is to provide improved means for throwing the ropes off of a bull wheel in a drilling rig, or the like.

A further object is to provide a throwing off device useful under any similar conditions, and comprising a drum formed with a spiral groove, rotation imparted to the drum, by frictional contact, serving to guide the ropes from the grooves of the bull wheel.

10 A further object is to provide for mounting the spiral drum on a crank element of a horizontal shaft adapted to be controlled by a lever, preferably positioned on the other side of the derrick, close to the usual bull

15 wheel brake lever.

With the foregoing and other objects in view, the invention consists in the novel construction and arrangement of elements described, illustrated and claimed, it being understood that modifications may be made within the scope of the claim, without departing from the spirit of the invention.

In the drawings forming part of this application,

25 Figure 1 shows a portion of a drilling rig in side elevation, the ropes leading to the bull wheel at the left, being adapted for engagement by the drum, shown in dotted line position.

30 Figure 2 is an elevation of the same structure, from another angle.

Figure 3 is a perspective view of a crank shaft adapted to mount the spiral drum, the shaft having an up-turned portion at one end, constituting a lever.

35 A portion of a rig is shown conventionally and includes the elements 10, 11, 12 and 13, a bull wheel at the left of the view being designated 14.

40 Ropes such as 15 pass over the wheel, and the latter is provided with grooves 16 for the accommodation of the ropes, and the object of the present device is to throw off the ropes when required.

In order to accomplish the result indicated 45 in the most efficient manner, I provide a horizontal shaft 18 having a crank portion 19 formed thereon, the shaft being mounted in bearings, such as 20 and including or having connected therewith a hand lever 21 preferably extending to the opposite side of the derrick, to a point close to the usual bull wheel 50 brake lever.

Carried by the crank portion 19 of shaft 18 is a drum 23 provided with a spiral groove 55 24, the groove preferably corresponding in size or cross section with the grooves 16 of the bull wheel 14.

In the full line position of Figure 1, reference being had especially to the spirally 60 grooved drum, the ropes passing over the bull wheel do not engage the grooves thereof, but in the dotted line position of the spiral drum 23, the drum is frictionally engaged, and the rotation of the spiral drum produces 65 lateral movement of the ropes, with the result that the latter are thrown off of wheel 14. This operation takes place when the lever 21 is thrown to the position of Figure 3. In the full line position of Figure 1 the lever 21 70 has placed the spiral drum out of service.

The bull wheel 14 is mounted on shaft 26, and this shaft carries a wheel 27 around which belt 28 passes, these elements having no particular bearing on the present improvement 75 which relates only to the throwing off device.

What is claimed is:

A device for throwing a rope from a wheel, said device comprising a spirally grooved drum mounted to impart lateral movement 80 to the rope with reference to the drum, and a lever controlled rock shaft of the crank shaft type mounting the drum for movement in an arc-shaped path while said drum maintains parallel relation with the axis of rotation of 85 the wheel.

In testimony whereof I affix my signature.

GUY P. SLATER.
